US0D1063862S

(12) **United States Design Patent** (10) **Patent No.:** **US D1,063,862 S**
(45) **Date of Patent:** **** Feb. 25, 2025**

(54) **ELECTRICAL CONNECTOR**

- (71) Applicant: **Delta Electronics (Shanghai) Co., Ltd.**, Shanghai (CN)
- (72) Inventors: **Hongming Li**, Shanghai (CN); **Donglin Fu**, Shanghai (CN); **Kai Dong**, Shanghai (CN)
- (73) Assignee: **Delta Electronics (Shanghai) Co., Ltd.**, Shanghai (CN)
- (**) Term: **15 Years**
- (21) Appl. No.: **29/892,508**
- (22) Filed: **May 18, 2023**

(30) **Foreign Application Priority Data**

- Feb. 15, 2023 (CN) 202330051902.8
- (51) **LOC (15) Cl.** **13-03**
- (52) **U.S. Cl.**
USPC **D13/146**
- (58) **Field of Classification Search**

(57) **CLAIM**

The ornamental design for an electrical connector, as shown and described.

DESCRIPTION

FIG. 1 is a front, bottom and right side perspective view of an electrical connector showing our new design;

FIG. 2 is a rear, top and left side perspective view thereof; FIG. 3 is a front, bottom and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

1 Claim, 9 Drawing Sheets
